[57] **ABSTRACT**

A process for the distillation of high boiling diacetylenically unsaturated compounds comprising subjecting said high boiling diacetylenically unsaturated compounds to distillation conditions within a distillation zone in the presence of a higher boiling inert hydrocarbon diluent, said diluent having a minimum boiling point at least 5°C higher than the boiling point of said diacetylenically unsaturated compound being distilled, the distillation being carried out under vacuum sufficient to maintain a maximum distillation temperature below 150°C.

DISTILLATION OF DIACETYLENICALLY UNSATURATED AROMATIC HYDROCARBONS

CROSS-REFERENCE TO RELATED APPLICATIONS

This application is a continuation-in-part of copending application Ser. No. 105,726, filed Jan. 11, 1971 and now abandoned.

BACKGROUND OF THE INVENTION

The present invention relates to the distillation of readily polymerizable unsaturated hydrocarbons. More particularly, the present invention relates to a process for the distillation of the readily polymerizable high boiling diacetylenically unsaturated aromatic hydrocarbons, i.e., diethynylbenzene, methyl diethynylbenzenes, whereby polymer formation is substantially reduced.

The diacetylenically unsaturated hydrocarbons such as diethynylbenzene, readily polymerize when subjected to elevated temperatures. These compounds are high boiling, i.e., diethynylbenzene boiling point approximately 190°C at atmospheric pressure, and even when high vacuum is used in their distillation, significantly elevated temperatures are still required in order to get a boil-up of the diacetylenically unsaturated compounds. Such elevated temperatures result in significant polymer formation with the attendant loss of desired product and the fouling and plugging of the distillation apparatus. The use of the well-known and widely used conventional polymerization inhibitors such as tert-butyl catechol, sulfur, hydroquinone, and the like, which work relatively effectively for most vinyl compounds, does not significantly, if at all, reduce polymer formation even in the high vacuum distillation of the diacetylenically unsaturated aromatic hydrocarbons.

It is an object of the present invention to provide a new and improved process for the distillation of high boiling diacetylenically unsaturated hydrocarbons.

Another object of the present invention is to provide a new and improved process for the distillation of high boiling diacetylenically unsaturated hydrocarbons whereby such hydrocarbons may be readily distilled with substantially reduced polymer formation.

Additional objects will become apparent from the following description of the invention herein disclosed.

SUMMARY OF THE INVENTION

The present invention, which fulfills these and other objects, is a process for the distillation of high boiling diacetylenically unsaturated compounds comprising subjecting said high boiling diacetylenically unsaturated compounds to distillation conditions within a distillation zone in the presence of a higher boiling inert hydrocarbon diluent, said diluent having a minimum boiling point at least 5°C higher than the boiling point of said diacetylenically unsaturated compound being distilled.

By means of the distillation process of the present invention, diacetylenically unsaturated compounds such as diethynylbenzene may be distilled at relatively high temperatures with substantially reduced polymer formation as compared to that normally obtained under

high vacuum distillation conditions alone and/or in the presence of conventional polymerization inhibitors.

DESCRIPTION OF THE PREFERRED EMBODIMENTS OF THE PRESENT INVENTION

The distillation process of the present invention is carried out in the presence of an inert hydrocarbon diluent higher boiling than the diacetylenically unsaturated hydrocarbons being distilled by at least 5°C at the pressure of the distillation. Such inert hydrocarbons include the higher boiling paraffins, naphthenes and aromatics including partially hydrogenated aromatics. In general, these inert hydrocarbons have boiling points of above 200°C at atmospheric pressure. The paraffinic hydrocarbons useful include both straight and branched chain while the naphthenic hydrocarbons include alkyl substituted naphthenes and polycyclic naphthenes. Aromatic hydrocarbons useful include the alkyl benzenes, alkyl naphthalenes, and the like, high boiling polycyclic condensed ring and noncondensed ring aromatics such as phenanthrene, anthracene, diphenyl, dimethyl diphenyl, and high boiling partially saturated aromatics such as tetralin, fluorene, acenaphthene, and the like. Particularly useful are the triethyl benzenes, tetramethyl benzenes, tetraethyl benzenes, tetralin, diphenyl, methyl diphenyl, methyl diethyl benzenes, naphthalene, methyl naphthalenes, and the like, as well as mixtures thereof. The choice of the particular inert diluent employed is most frequently based on such practical considerations as availability, costs, ease of handling, i.e., whether normally liquid or solid, and like considerations. Additionally, it is preferable to take into consideration the apparent efficiency of the distillation apparatus since for a clean separation, the boiling temperature difference between the diacetylenically unsaturated compound and the inert diluent is greater as the distillation apparatus becomes less efficient. The primary considerations, in accordance with the present invention, are that the inert diluent must have a minimum boiling point at least 5°C, preferably 10°C above the maximum boiling point of the diacetylenically unsaturated compounds being distilled and that the inert diluent be completely inert to reaction with the unsaturated compound. For distilling such compounds as diethynylbenzenes, the preferred inert hydrocarbon diluents are the tri- and the tetraethyl benzenes, the tetramethyl benzenes and the mixed ethyl, methyl and propyl substituted benzenes boiling above 200°C.

In the distillation process of the present invention, it is generally desirable to carry out the distillation under substantially reduced pressure. Usually, the diacetylenically unsaturated aromatic compounds are distilled at a pressure sufficient to reduce the boiling point of the diacetylenic compound being distilled to below 150°C, preferably below 80°C. To effect such temperatures, pressures ranging below about 200 mm. Hg, preferably below 20 mm Hg, are employed.

While the present distillation process is primarily directed toward the distillation of diacetylenically unsaturated compounds, it may be employed in the distillation of other high boiling readily polymerizable unsaturated compounds such as divinyl aromatics, monoacetylenically unsaturated hydrocarbons, and the like. However, the process of the present invention is most useful when employed in the distillation of the readily polymerizable diacetylenically unsaturated aromatic

hydrocarbons such as diethynylbenzenes, ethynylpropynyl benzenes, and the like, as well as such hydrocarbons containing non-hydrocarbon substituents such as halogens, i.e., chlorine and bromine, amino groups, nitro groups, acid groups, hydroxy groups and the like. In its preferred application, the distillation process of the present invention is applied to the distillation of diethynylbenzenes.

The amount of inert hydrocarbon diluent employed may vary widely, however, the amount employed will most often represent a concentration of greater than 15 volume % of the mixture resulting from its admixture with the diacetylenically unsaturated compounds being distilled. Preferably, however, the concentration of such inert hydrocarbon diluent in such mixture is greater than 35 volume %. While above these limits, virtually any amount of inert hydrocarbon diluent may be employed, seldom is it used in concentration of greater than 60 volume % in its admixture with the diacetylenically unsaturated compounds being distilled.

In carrying out the process of the present invention as a continuous operation, the feed containing diacetylenically unsaturated compounds and the inert hydrocarbon diluent may be both continuously introduced in pre-admixture with one another or each may be continuously introduced separately into the distillation apparatus. In the continuous distillation of the diacetylenically unsaturated compounds, usually the diacetylenic compounds are continuously taken over-

EXAMPLE I

To demonstrate the efficacy of the present invention a series of seven stability tests were carried out by heating diethynylbenzene for several hours at 200°F (93°C). In one of the tests, diethynylbenzene was heated alone and in tests 2 through 5 various inhibitors were added while in tests 6 and 7, heating was in the presence of an inert hydrocarbon diluent. The specific composition of the material subjected to the above conditions in each of the seven tests were as follows:

TEST

- No. 1 Diethynylbenzene
- No. 2 Diethynylbenzene containing 0.16 wt. % t-butyl catechol (TBC)
- No. 3 Diethynylbenzene containing 0.1 wt. % TBC and 0.5 wt. % sulfur
- No. 4 Diethynylbenzene containing 0.16 wt. % hydroquinone
- No. 5 Diethynylbenzene containing 0.35 wt. % Polygard*
- No. 6 Diethynylbenzene in 1:1 admixture with tetraethyl benzene
- No. 7 Composition of 6 containing 0.1 wt. % TBC

*Registered trademark of Naugatuck Chemical Division of United States Rubber Co.

The character of the heated material was periodically observed and recorded with reference to polymerization. Table I following presents the results of the periodic observations for the seven tests.

TABLE I

Number of Hours at 200°F	Test No. 1	Test No. 2	Test No. 3	Test No. 4	Test No. 5	Test No. 6	Test No. 7
24	dark	dark	dark	dark	sl. dark	clear	clear
36	solid	solid	solid	solid	solid	clear	clear
60	—	—	—	—	—	darker	darker

head or as a side draw, if lighter materials are present, with the heavier materials and the inert hydrocarbon diluent being continuously taken from the bottom of the distillation apparatus. If desired, of course, the distillation process of the present invention may be carried out batchwise or semi-continuously with intermittent introduction of either the diacetylenically unsaturated compound containing feed or the inert hydrocarbon diluent.

The type of distillation equipment employed for the process of the present invention may be any of that conventionally employed and may range in efficiency from simple flash distillation apparatus to very high efficiency multiray distillation columns. As hereinabove indicated, however, as the efficiency of the distillation apparatus goes down, it frequently is desirable to increase the temperature spread between the diacetylenically unsaturated compounds being distilled and the inert hydrocarbon diluent being used.

To further describe and to specifically exemplify the present invention, the following examples are presented. These examples are not to be construed as limiting the scope of the present invention, however.

EXAMPLE II

A series of four tests was carried out to demonstrate the effect of the concentration of inert hydrocarbon diluent in the diacetylenically unsaturated compound. In each test, diethynylbenzene was the diacetylenically unsaturated compound and triethylbenzene was the inert hydrocarbon diluent. In all tests, the mixture was heated at 240°F. Table II below describes the character of the diethynylbenzene after various time periods for each of the four test runs.

TABLE II

No Hours heated at 240°F	Concentration of triethylbenzene in diethynylbenzene			
	15%	34%	44%	53%
2	dark	OK	OK	OK
4	dark	sl. dark	OK	OK
6	Viscous	dark	dark	dark
9	More viscous	Viscous	dark	dark
12	Solid	solid	sl. viscous	same
14	—	—	Viscous	same
15	—	—	Solid	sl. viscous
22	—	—	—	Solid

EXAMPLE III

To further demonstrate the present invention, two separate fractionations were carried out on 1,500 grams of the same 95% by weight diethynylbenzene fraction. In one fractionation, referred to as Run A, the diethynylbenzene fraction was added to the stillpot and the diethynylbenzene distilled therefrom. In the other fractionation, referred to as Run B, the diethynylbenzene fraction was diluted with an equal volume of tetraethylbenzenes and then the diethynylbenzene distilled overhead. In both Run A and Run B, the distillation was carried out at an overhead pressure of 1-2 mm Hg and the overhead product was 99% by weight diethynylbenzene. In Run A the overhead temperature was 43°-47°C while in Run B, the overhead temperature was 47°C. The maximum stillpot temperature in Run A was 100°C and Run B was 110°C. It was found that in Run A, a substantial amount of polymer coated the wall of the stillpot while in Run B, no polymer formed in the stillpot.

What is claimed is:

1. A process for the distillation of high boiling diacetylenically unsaturated aromatic hydrocarbons comprising subjecting to distillation conditions within a distillation zone a distillation mixture consisting es-

20

sentially of said high boiling diacetylenically unsaturated aromatic hydrocarbon and a high boiling aromatic hydrocarbon diluent, said diluent having a minimum boiling point at least 5°C. higher than the boiling point of said diacetylenically unsaturated aromatic hydrocarbons being distilled and being present in an amount greater than 15 volume percent of the mixture resulting from its admixture with the diacetylenically unsaturated compounds being distilled, said distillation being carried out under vacuum sufficient to maintain a maximum distillation temperature below 150°C., and separating overhead pure diacetylenically unsaturated aromatic hydrocarbon whereby polymerization of said diacetylenically unsaturated aromatic hydrocarbon during distillation is substantially prevented.

2. The process of claim 1 wherein said diacetylenically unsaturated aromatic hydrocarbon is diethynylbenzene.

3. The process of claim 1 wherein said high boiling aromatic hydrocarbon is one selected from the group consisting of triethyl benzenes, tetramethyl benzenes, tetraethylbenzenes, tetralin, diphenyl, methyl diphenyl, methyl diethyl benzenes, naphthalene, methyl naphthalenes, and mixtures thereof.
